1,982,582

COLD WATER INLET CONTROL VALVE

Luther D. Lovekin, Villanova, Pa., assignor to
 Kitson Company, Philadelphia, Pa., a corpora-
 tion of West Virginia

Application October 26, 1932, Serial No. 639,551

6 Claims. (Cl. 137—161)

My invention relates to a combination fitting for application to a boiler or water heater with particular reference to a boiler or water heater permitting a back flow of water out of the boiler or heater into the cold water supply line thereof when or if the pressure inside the boiler or heater abnormally rises from expansion of the heated water.

A purpose of my invention is to combine a cold water inlet fitting at a boiler or heater of the character indicated with an emergency shut-off of the fuel to the boiler or heater.

A further purpose is to provide a desirable form of combination double conduit fitting in which the flow in one conduit of the fitting is adapted to effect a closure of flow through the other conduit thereof if the temperature of the first flow becomes unduly high.

A further purpose is to use an abnormal back-
 20 ing of hot water out of a boiler or heater into the cold water supply line thereof to operate an emergency shut-off of the fuel to the boiler or heater.

A further purpose is to use the abnormal in-
 25 creased and increasing volume of the water inside a heater of the character indicated incident to any abnormal high and increasing temperature of the water of the heater to shut off the fuel to the heater before the heater can generate steam.

Further purposes will appear in the specification and in the claims.

I have elected to show one main form only of my invention, showing however minor detail 35 modifications and selecting a main form and minor modifications thereof that are practical and efficient in operation and which well illustrate the principles involved.

This application is a continuation in part of 40 my co-pending application, now Patent No. 1,892,674, for a Cold water inlet control valve.

Fig. 1 is a vertical cross section through an embodiment of my invention.

Fig. 2 is a side elevation of a portion of a modification of my invention with parts in vertical cross section.

I show in Figure 1 a particularly advantageous form of thermostatic shut down valve, using a bi-metal strip 47 as a thermostatic latch, holding 50 open a valve 22' away from its seat 17' until or unless thermostatic expansion of the latch member 47 incident to abnormally high temperature releases the valve to snap closed responsive to the action of a spring 30'.

55 In Figure 1 the solid shank 15' that threads

into one of the outlets of the T 12 forms a mount for the bi-metal expansion strip 47 and presents an upwardly directed cup 48 that makes threaded connection at 49 with a downwardly directed cup 50 which has an upwardly directed shank 60 51 threading into and carrying the valve 11'.

The thermostat element 47 has one end fastened at 52 to the bottom of the cup and bends upwardly to present a hook 53 normally above an upwardly directed shoulder of a head 54 at 65 the lower end of a valve stem 21'.

The valve is of the globe type having inlet at 19' and outlet at 20'.

The movable portion of the valve includes an assembly mounted on the stem 21', the stem 70 carrying a skirt 23', the valve element 22', washer 42' and nut 43'.

The skirt 23' is upwardly counterbored to receive the spring 30' and loosely telescopes into an upwardly directed guiding counterbore of the 75 shank 51.

The valve assembly is spring pressed upwardly by the spring 30' which is compressed between the bottoms of the counterbores in the shank 51 and the skirt member 23'.

At normal temperature the thermostatic strip 47 has a position adapting the hook 53 to latch above the upwardly directed shoulder of the stem head 54, thereby holding the stem and valve assembly down against the closure pressure of the 85 spring 30'.

The valve element 22' is held to its skirt member 23' by the washer 42' and nut 43', the stem being shown projecting somewhat upwardly at 55 in position to be engaged by the downwardly 90 directed end of a push rod 56, the push rod being axially aligned with the valve and valve stem and carried in a longitudinally bored and counterbored removable plug 57 that is normally covered by an outer cap 58.

The push rod carries a head 59 at its lower end, a cap 60 at its upper end and is spring pressed upwardly by a spring 61.

In the event of abnormally high temperature in the member 12, the heat transmitted by conduction through the shank 15', outwardly deflects the thermostat element 47 to release the hook from over the upwardly directed shoulder of the valve stem, permitting snap closure of the valve which stops the flow of fuel through the 105 valve 11 to the heater.

In resetting the valve to open position, the cap 58 is taken off and the push rod depressed downward, which causes the tapered head 54 of the valve stem to slide past the hook which auto- 110

matically latches back of the head, the lower temperature incident to the closure of the valve having resulted in a return of the bi-metal strip to its normal position.

5 Instead of using the conduction through a plug such as that shown at 15' in Figure 1 to heat the bimetallic element, the plug may be made of the character of that shown at 15' in Figure 2, where the lower wall 62 of the plug may be as thin as 10 any normal wall of a fitting. The fitting shown is of L type, providing for cold water inlet at the bottom. Obviously, whether the fitting be of L type or another type is a mere detail.

15 It will be obvious that the term heater is broad enough to include not only what is normally so called, but any type of boiler or tank in which a corresponding heating function is performed.

20 In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the 25 reasonable spirit and scope of my invention.

I claim:

1. A double conduit fitting, a valve in one of the conduits pressed toward closure, an emergency actuated device including a compartment 30 having a heat conducting connection to the other conduit, a thermostatic latch in said compartment, and connections between the latch and valve adapted to normally hold the valve open and releasing the valve to closure at an abnormally high temperature incident to abnormally 35 high heat in the said other conduit.

2. A T fitting, an emergency shut-off valve 40 pressing toward closure, a casing for said valve having a well connecting to the T at one outlet thereof thereby providing a heat connection between the interiors of the T and well, and a thermostatic latch inside the well adapted to normally hold the valve open and releasing the 45 valve if the temperature within the well rises abnormally incident to abnormally high temperature within the T.

3. An emergency fuel shut-off valve including 50 a conduit having inlet and outlet compartments, a wall between the compartments having an opening connecting the compartments, a valve adapted to close the opening and pressed toward its position of closure, a valve stem, a second conduit for fluid, a chamber surrounding said stem fastened laterally to one of the compartments 55 of said first mentioned conduit and presenting a heat conducting terminal for connection to said second conduit for fluid, and a thermostatic element mounted in the chamber adapted to nor-

mally latch the valve open and releasing the valve if the temperature within the chamber rises abnormally.

4. An emergency fuel shut-off fitting including 80 a conduit having inlet and outlet compartments, a wall between the compartments having an opening connecting the compartments, a valve adapted to close the opening, a valve stem extending from the valve in a direction laterally away from the opening, a spring pressing the valve toward its position of closure, a second conduit for fluid, a chamber surrounding said stem fastened laterally to the conduit containing the compartments and presenting a heat conducting terminal for connection to said second conduit, a head on the stem within the chamber, and a thermostat mounted in the chamber adapted 90 during normal temperature within the chamber to latch back of the head to hold the valve open and at abnormally high temperature within the chamber to release the head to permit valve closure.

5. An emergency fuel shut-off fitting including 95 a conduit having inlet and outlet compartments, a wall between the compartments having an opening connecting the compartments, a valve adapted to close the opening, a valve stem extending from the valve in a direction laterally away from the opening, a spring pressing the valve toward its position of closure, a second conduit for fluid, a chamber surrounding said stem fastened laterally to the conduit containing the compartments and presenting a heat conducting terminal for connection to said second conduit, a head on the stem within the chamber, a thermostat mounted 100 in the chamber adapted during normal temperature within the chamber to latch back of the head to hold the valve open and at abnormally high temperature within the chamber to release the head to permit valve closure, and a push rod 105 mounted upon the side of the fitting away from the valve, spring pressed away from the valve, substantially aligned with the valve and adapted when depressed to open the closed valve for relatching the valve open.

6. A T fitting, an emergency shut-off valve comprising a casing and a valve pressed toward closure, a compartment connected at one end to one outlet of the T and connected at the other end to the valve casing and providing a heat connection between the interiors of the T and compartment, a thermostatic latch inside the compartment adapted to normally hold the valve open and releasing the valve if the temperature within the compartment rises abnormally, incident to abnormally high temperature within the T.
